United States Patent Office

Des. 233,577
Patented Nov. 12, 1974

233,577

CHEST OF DRAWERS OR THE LIKE

Huey T. Keller, High Point, N.C., assignor to Gillespie
Furniture Company, Los Angeles, Calif.

Filed Feb. 1, 1973, Ser. No. 328,607

Term of patent 14 years

Int. Cl. D6—04

U.S. Cl. D6—154

FIG. 2

FIG. 1

FIG. 3

FIG. 1 is a front elevational view of the chest of drawers or the like showing my new design;

FIG. 2 is a top plan view thereof; and

FIG. 3 is an end elevational view of such design, the opposite end being substantially a mirror image of that shown.

I claim:

The ornamental design for a chest of drawers or the like, as shown and described.
